4 Claims. (Cl. 67—7.1)

1

The present invention relates to pocket lighters of the type having a lighter body and a hinged cover, and in which ignition sparks are produced by a flint urged against a friction wheel which is operated by a finger actuated driving roller.

In pocket lighters having hinged covers, the facility and commodity with which the cover may be opened and closed in use, is of particular importance. In such lighters, usually a spring determines the open and the closed position of the cover as positions of stable equilibrium. For convenient and reliable operation of the cover, it is necessary that the pivoting movement of the cover can be effected with the least possible friction.

According to the present invention a blade spring is inserted between the body of the lighter and the cover, said spring being subjected to flexure and compression upon opening or closing of the cover. The blade spring tensioned in appropriate manner between cover and body of the lighter operates so that the cover, by a spring toggle joint action, can be tilted through a position of unstable equilibrium from closed to open position, and when the blade spring is disposed in appropriate manner, this pivoting movement is effected practically almost without friction, so that the cover of the pocket lighter can be operated very easily and conveniently.

According to a further feature of the invention the flint of the pocket lighter is lodged in an open channel which may be formed by a sleeve, so that the length of the flint is visible when the lighter is opened. Preferably the sleeve is laterally open and a spring operated lever arm penetrating through the opening bears against one end of the flint in the sleeve and urges it against the friction wheel.

The accompanying drawings represent by way of example three embodiments of the present invention.

Fig. 1 shows a lighter according to the first example in elevation.

Fig. 2 is a vertical section along the line II—II of Fig. 5, with the cover in open position.

Fig. 3 is a vertical section along the line III—III of Fig. 5 with the cover in closed position.

Fig. 4 is a vertical section along the line IV—IV of Fig. 5.

Fig. 5 is a top plan view of the lighter with the opened cover shown in section.

Fig. 6 is a view from below showing the bottom of the lighter.

Fig. 7 is a view in elevation of a modified lighter.

Fig. 8 is a vertical section along the line VIII—

2

VIII of Fig. 11, with the cover shown in open position.

Fig. 9 is a vertical section along the line IX—IX of Fig. 11, showing the cover in closed position.

Fig. 10 is a vertical section through the lighter along the line X—X of Fig. 11.

Fig. 11 is a top plan view of the lighter, showing the opened cover in section.

Fig. 12 is a view of the bottom of the lighter.

Fig. 13 shows a further modification of a lighter in elevation, partially in section along the line XIII—XIII of Fig. 14.

Fig. 14 is a top plan view of the lighter showing the opened cover in section.

Fig. 15 is a vertical section along the line XV—XV of Fig. 14.

Fig. 16 is a perspective view of the flint sleeve.

Referring to Figs. 1 to 6, the represented pocket lighter comprises a body 1 which may consist of

20 light metal. The cover 2, preferably also of light metal, is hinged to the body 1 by means of the axis 3. As can be recognized from Figures 2, 3 and 5, a blade spring 7 formed by a thin, rectangular piece of steel plate, is clamped by two 25 opposed sides of the rectangle between two notches 36 and 37, one of which notches 36, as particularly Figure 3 clearly shows, is disposed in the body 1 of the pocket lighter and the other, 37, in the cover 2. Both notches are parallel to

30 the axis of rotation 3 of the cover. When opening or closing the cover 2 the distance between the two notches decreases first from an initial value until a minimum, and then increases again until a final value. During the pivotal stroke of

35 the cover 2, the blade spring 7 clamped between the notches 36 and 37 with an appropriate initial tension, is first compressed and subjected to flexion, and then extends again. Since the two

40 in the notches like knife edges, practically any friction of the spring mechanism is avoided, with the most simple construction of the resiliency to be imagined. As a rule the mutual position of

45 the two notches 36 and 37 will be chosen so that the minimum of their distance is reached when approximately the cover 2 is half open. The half opened cover 2 is at unstable equilibrium and has the tendency, when deviating from this position

45 of unstable equilibrium to tilt resiliently either downwardly or upwardly.

The spring 7, instead of being made of a plane piece of steel plate, may consist also of an undulated piece of steel plate, in which the undulations are parallel to the two notches 36 and 37, and accordingly parallel to the axis of rota-

tion 3 of the cover 2. The undulated construction of the spring has the advantage that for approximately the same spring force, the steel plate can be made stronger, thus more solid.

In order to be able to open the pocket lighter conveniently with the thumb of the right hand, the cover 2, as can be seen from Figures 1 and 2, slightly projects beyond the vertical front face of the body 1. In order to enable closing of the cover in similar convenient manner, the axis of rotation 3 and the hinge between the cover 2, and the body 1 are so disposed, that in open position the cover 2 projects about for its thickness beyond the vertical rear face of the body 1, as can be recognized from Figure 2 and therefore the cover can be closed preferably with the bend of the index of the right hand.

The correct operation of the cover, however, does not depend only on the expedient formation of the spring mounting, also the disposition of the axis of rotation is of great importance. It is to be recommended to provide only two journals and to dispose them at a maximum distance, that is at opposite ends of the axis of rotation 3. In the represented example, accordingly, as can be recognized particularly from Figure 5, the axis 3 is firmly pressed into the cover 2 and rotatably mounted with both its ends in the body 1 of the pocket lighter.

A further feature of the invention resides in the disposition of the flint 20 in such manner that it can be directly seen in its longitudinal extension when the cover is opened. The flint 20 is lodged, as can be recognized from Figure 4, in an upwardly open channel 19 provided in the upper side of the body 2. This disposition has two advantages. First, each time the cover is opened, the length of the flint pin can be judged. The user is thus capable of timely exchanging a flint which is nearly used up. Second, the manufacture of the pocket lighter is simplified and cheapened, because the upwardly open channel, for example, can be produced by hot pressing in a single operation together with the formation of the remaining portion of the upper side of the body 1. The flint 20 is prevented from falling out of the channel 19 by the friction wheel 18 which is formed with a shoulder 38 at its upper end under which the flint 20 is placed, pressed by the nose 22 of the pressure lever 21. The pressure lever 21 is rotatably mounted on a pin 24, as shown by Figures 3 and 4. The pin 24 is pressed into the body 1 of the pocket lighter. The bearing 23 of the pressure lever 21 on the pin 24 is surrounded by a coiled spring 23, which engages with one end a small bore in the body of the pocket lighter, with the other end a similar small bore in the pressure lever 21. When mounting the pressure lever 21 an initial tension is imparted to this spring 23, so that the nose 22 of the pressure lever 21 forcibly presses the flint 20 against the friction wheel 18 at any length which the flint may have. The upwardly projecting portion of the nose 22 on the pressure lever 21 enables to relieve the flint 20 from pressure and to remove it from the channel 19 or to place a new flint in the latter.

The friction wheel 18 having as shoulder 38 at its free end, is provided with a bore having a left hand thread and thus forms a nut on the free end of the axis 17 of the driving roller 16. When mounting the ignition mechanism, first the driving roller 16 is placed into the recess 42 provided in the body 1 and then the axis 17 is pressed from above into the driving roller 16, so as to

become fixed in this latter. After this operation the friction wheel 18 having a left hand thread can then be screwed on the axis 17 and tightened with a pin spanner engaging into the two holes 53 provided in the free end face of the friction wheel 18.

The fuel reservoir consists of the proper provision chamber 8 conveniently filled with cotton, and of the wick chamber 11. These two chambers are communicating by an opening 10. Such a division of the fuel reservoir has different advantages. The provision chamber 8 can be bored as a longitudinal hole by means of a milling cutter. In the same clamped position of the blank 15 from which the lighter body is to be produced, the wick chamber 11, with the thread for the filling screw 14, is cut out from the body 1 by means of appropriate drills. Afterwards the opening 10 must be broken through by means of a milling cutter working at an angle. Now the provision chamber 8 can be filled with cotton and a plug 9 destined to close the hole through which the drills were inserted, can be pressed in the bottom so as not to be detachable. Then it is possible to draw the wick 12 into the wick conduit 13 through the opening for the filling screw 14, independently of the cotton filling in the provision chamber 8. The upper end of the wick conduit 13 is formed by the wick tube 15 which slightly projects beyond the body 1 of the pocket lighter.

The described division of the fuel reservoir has further the advantage that the filling screw 14 is screwed into the integral bottom of the body 1 and not into the pressed plug 9.

Finally it appears that the small provision of petrol which is always present in the wick chamber 11 and not bound to the cotton filling, provides a longer burning flame upon ignition of the wick.

A special air conduit 25 leads from the upper face of the body 1 near the wick tube 15 (Figs. 3 and 5) to the recess 42, in which the driving roller 16 is inserted. This air duct 25 is not visible from the exterior on the pocket lighter, but allows for a better feeding of air to the flame of the wick.

In order to prevent the evaporation of fuel when the cover is closed, a metal cap 4 is placed over the wick tube 15. This cap 4 is movable in a sleeve 6, but cannot move out of it so as not to be lost. The sleeve 6 is pressed into the cover 2 and between the cover 2 and the bottom of the cap 4 there is a small spring 5 which tends to press the cap 4 downwardly. In this manner a tight closure of the wick tube is obtained, provided naturally that the air duct 25 discharges outside of the cap 4.

The lighter according to Figures 1 to 6 is characterized by a minimum of screw connections. Besides the filling screw 14 and the exchangeable friction wheel 18 no screw connections at all are present in the construction.

The shape of the cover 2 and of the upper part of the body 1 allows to produce these parts in simple manner by warm pressing or by die-casting. When warm pressing as well as when die-casting, only the holes for the axis of rotation 3, the pin 24, the wick sleeve 15, the axis 17 and the air holes 25 are to be drilled as additional machining from the upper end of the body. All these borings, with the exception of the bore for the axis of rotation 3 of the cover, are effected vertically from top to bottom. From the lower end of the body 1 the provision chamber 8, the wick chamber 11 with the thread for the filling

screw 14 and the conduit 13 for the wick 12 must be bored. When producing the body 1 by die-casting, the provision chamber 18 and the wick chamber 11 can be left open already when die-casting. The two notches 36 and 37 for mounting the spring 7 are made in the most simple manner by striking or engraving by means of a chisel-like guided tool.

A particular feature which gives a pleasant aspect to the present construction, consists in that the cover 2 rests on the body 1 in a plane beyond which no parts project besides the nose 22 for operating the pressure lever 21.

A further advantage of the described ignition mechanism comprising the flint 20 placed in the channel 19 from above, and pressed against the friction wheel 18 by the pressure lever 21, consists in the possibility of a compact disposition of these parts, which leaves approximately one half of the upper face of the body 1 free, so that the hinge with the axis of rotation 3 of the cover 2 and the blade spring 7 occupying the other half, can be made strong.

In the modification according to Figs. 7 to 12 the represented pocket lighter comprises a body 1' preferably made of light metal by die-casting. This body is inserted in a drawn sleeve 26, preferably of light metal plate, and tightly connected with this sleeve by a synthetic substance (synthetic resin, varnish) resistant against fuel. To the body 1' a cover member 2, preferably also made of light metal by die-casting, is hinged by means of the axis 3. The cover member 2 is inserted into a drawn lid 27, preferably also of light metal plate and fixed to this latter by means of a synthetic substance.

The blade spring 7 mounted between the body 1' and the cover member 2 for the convenient opening and closing of the cover is mounted in analogous manner as the spring in the example according to Figs. 1 to 6.

The body 1' is formed with an extension 28 reaching to the bottom of the drawn sleeve 26. This extension serves two purposes. First it is provided with a recess 42 in which the driving roller 16 is mounted by its axis 17, and second it is provided at the bottom of the sleeve with a foot 54 having a threaded bore for receiving the filling screw 14.

In contradistinction to the example according to Figs. 1 to 6, the flint 20 is placed in a channel 33 made by an appropriately cut out and bent piece of sheet material. This channel 30 is provided with a flat extension 32 having a bore by means of which the channel is rotatably mounted on the upper end of the axis 17 for the driving roller 16. The friction wheel 18 which is screwed by means of a left hand thread on the upper end of the axis 17, rotatably maintains the channel 30 on the axis 17. In proximity of the friction wheel the channel 30 is further provided with two flaps 31, surrounding the flint 20 and preventing it from falling out of the channel.

The feed of the flint is effected by the pressure lever 21, having a pin 33 on its free end which penetrates into the channel 33. The pressure lever 21 firmly connected with the axis 24, is rotatably mounted in the bearing sleeve 35 of the pressure lever. The coiled spring 23 exerting pressure on the axis 24, is clamped with one end in a slit 51 at the lower end of the axis 24 and penetrates with the other end in the bearing sleeve 35 for the pressure lever. This construction has the great advantage that the pressure lever 21, the axis 24, the bearing sleeve 35

and the coiled spring 23 can be assembled all together outside of the body 1' and then pressed into the corresponding bore 50 in the body 1' together with the bearing sleeve 35. For moving the pressure lever 21 against the action of the spring 23, the lever is provided at its upper side with a slot 34, in which a coin can be inserted. When the lever is turned by means of the coin in clockwise direction in Fig. 11, the pin 33 moves out of the channel 30 for the flint 20; then by means of a slight return rotation of the driving roller, the channel 30 can be swung outwardly and a new flint can be inserted. Swinging the channel 30 with the flint 20 inwardly 15 and reinserting the pin 33 into the channel is inversely effected in analogous manner.

The cap 4 for sealing the wick is carried on a blade spring 29, which is secured between the cover member 2 and the drawn sleeve 27 of the cover.

The drawn sleeve 26 and lid 27 can be made particularly thin, when they are stiffened by giving them a profile as represented in Figures 7, 11 and 12. This construction results in a pocket lighter of particularly small weight and having a comparatively large fuel reservoir.

In the use of the lighter, the portions around the friction wheel 18 and the wick 12 are particularly exposed to getting dirty. It is recommended therefore, to colour black the surface of body 1' and the interior of the cover 2 and the lid 27 which is visible when opening the cover, while the visible surface when the cover is closed can be maintained at a light shade (gold or silver shade). A particularly advantageous treatment of the surface, when the sleeve 26 and the lid 27 are drawn from light metal, is the anodic oxidation. The body 1' and the cover, when they are made as die-cast parts, generally cannot be 40 anodically oxidized, but anodic oxidation also of these parts is possible when the layer of oxide is given a black colouring, because with black colouring the spots and streaks generally present on anodically oxidized surfaces of die-cast parts are not visible.

As in the previous example, the cover 2 or lid 27 slightly projects beyond the body 1' when it is in the closed position, and also projects beyond the body 1' when it is in open position, thus permitting operation of the lighter by means of a single hand.

In the modification according to Figs. 13 to 16, the body 1' of the lighter is preferably made of light metal. The cover 2 is hinged on the body 1' by means of the axis 3. The wick cap 4, enclosing the free end of the wick when the cover 2 is closed, is secured to the cover 2 by means of a blade spring 29.

A recess 40 is provided in the upper face of the body 1', in which is disposed the curved blade spring 7 maintaining the cover 2 in open and in closed position. The recess 40 extends from the side of the body 1' receiving the axis 3 of the cover until about the middle of the upper face of the body, so that the front half 41 of the upper face is ready to receive the different members of the ignition device.

The body 1' is provided with a recess 42 in which is disposed the finger roller 16 for driving the friction wheel by its axis 17. The upper end of the axis 17 is provided with a left hand thread and projects from the upper face 41, so that the friction wheel 18 can be screwed thereon. The flint 20 is inserted in a sleeve 44 which is cut out 75 and bent of sheet material. The sleeve 44 has

an extension 45 with a bore 46 engaged over the end 43 of the axis 24 and maintained between the friction wheel 18 and the upper face 41 of the body 1, so that the sleeve 44 is rotatable about the centre of the axis 17. The sleeve 44 is provided with an opening 47 along one side thereof, through which penetrates the pressure lever 48 into the interior of the sleeve, in order to bear against the end of the flint 20, to prevent this latter from falling out and press it against the friction wheel 18.

The pressure lever 48 is pressed into the head 49 of an axis 24 rotatable in the bearing sleeve 35. The axis 24 is surrounded by a coiled spring 23 disposed in a recess 50 in the body 1. The lower end of the spring 23 penetrates into the slotted end 51 of the axis 24, while the upper end of the spring penetrates into the bearing sleeve 35 pressed firmly into the recess 50. The spring is thus tending to turn the axis 24 and the pressure lever 48 in that direction in which the pressure lever bears against the flint 20, in order to press the latter against the friction wheel 18.

The head 49 of the axis 24 is provided on its upper side with a slot 52, which is approximatively directed at right angles to the pressure lever 48. A coin can be inserted for example into this slot in order to pivot the head with the pressure lever against the action of the spring 23, in clockwise direction in Fig. 14 out of the sleeve 44, when a new ignition pin is to be introduced into the sleeve. After the pressure lever 48 has been moved out of the sleeve 44, the sleeve can be turned about the axis 17 in counter-clockwise direction in Fig. 14 until the end of the sleeve projects slightly beyond the side face of the body 1, so that the new flint can be conveniently introduced.

The end 48' of the pressure lever 48 bearing against the flint 20 is upwardly bent transversely to the sleeve 44. In this manner it will be prevented that for example when the finger roller 16 is turned in counterclockwise direction, an unintentional pivoting movement of the sleeve 44 capable of turning about the axis 17, is effected because the turned up end 48' of the pressure lever cannot penetrate through the lateral opening 47 of the sleeve.

The sleeve 44 is preferably made of steel plate and the inner diameter of the sleeve is made so great, that the flint 20 is elastically maintained by the friction of the sleeve wall. When in this case the pressure lever 48 is turned out of the sleeve for the purpose of introducing a new flint, the old, soon used up flint piece remains in the sleeve and does not fall out, and moreover this piece cannot turn when a new flint is introduced, so that the engagement of the end of the flint piece adapted to the curvature of the friction wheel 18, with the friction wheel is conserved and the formation of ignition sparks is not prejudiced.

When the lighter body 1 and the cover 2 are made of light metal, their outer surface can be anodically oxidized. Also the driving roller 16 and the filling screw in the bottom of the body can be made of light metal and anodically oxidized in the same manner as the outer surface of the lighter.

I claim:

1. In a pyrophoric lighter, a prismatic lighter body of substantially rectangular transverse section, a cover hingedly connected to the lighter body along one short side of the rectangular upper face of the lighter body, said upper face being provided with a recess extending from said

short side to which the cover is connected to substantially the median transverse axis of said upper face, a blade spring lodged in said recess and extending substantially on the level of the axis of said hinge connection, said blade spring having one end engaging said cover and the opposite end bearing against the lighter body, said spring being subjected to buckling stress and tending to hold the cover in fully open or fully closed position, a wick projecting from the surface portion of said upper face of the lighter body situated between said recess and the short side of the upper face opposite that where the cover is connected, a friction wheel mounted on said surface portion, a flint coating with said friction wheel, a longitudinally slotted guide tube for said flint pivotally mounted on the axis of said friction wheel, the lighter body being provided with a bore extending downwardly from said surface portion at a point laterally of said guide tube, a lever arm pivotally mounted in said bore and extending into the guide tube for the flint through said longitudinal slot thereof, and a torsional spring engaged in said bore for urging said lever arm to apply the flint against the friction wheel.

2. A pyrophoric lighter as claimed in claim 1, wherein said longitudinally slotted guide tube for the flint is formed of a piece of bent sheet material, provided with an apertured extension engaged on the axis of said friction wheel between one face of the wheel and said surface portion on the upper face of the lighter body.

3. In a pyrophoric lighter, a prismatic lighter body of substantially rectangular transverse section, a cover hingedly connected to the lighter body along one short side of the rectangular upper face of said body, said upper face being provided with a recess extending from the hinge connection to substantially the median transverse axis of said rectangular upper face, a blade spring lodged in said recess and extending substantially on the level of the axis of said hinge connection, said blade spring having opposite ends abutting against an end wall of the recess and against said cover for holding the cover in fully open or fully closed position, an igniting mechanism mounted on the lighter body between said end wall of the recess and the short side of the lighter body opposite to said hinge connection, said igniting mechanism including a rotatable friction wheel having its axis extending at right angles to said upper face of the lighter body, a flint coating with the friction wheel, a laterally open guide sleeve for the flint, said sleeve having an extension pivotally mounted on the axis of the friction wheel and engaged between the friction wheel and said upper face of the lighter body, a plug rotatably engaged in a recess in said upper face, a lever arm carried by said plug and extending into said laterally open guide sleeve, a coiled spring within said recess tending to turn said plug for urging said lever arm to apply the flint against the friction wheel, said plug having an upwardly open slot adapted to be engaged for turning the plug against the action of said coiled spring to remove said lever arm from the flint tube.

4. In a pyrophoric lighter, a prismatic lighter body of substantially rectangular transverse section, a cover hingedly connected to the lighter body along one short side of the rectangular upper face of said body, said upper face being provided with a recess extending from the hinge connection to substantially the median transverse axis of said rectangular upper face, a blade spring

lodged in said recess and extending substantially on the level of the axis of said hinge connection, said blade spring having opposite ends abutting against an end wall of the recess and against said cover for holding the cover in fully open or fully closed position, the upper face portion of said body between said end wall of the recess and the short side of the lighter body opposite to said hinge connection being flat and provided with three parallel bores extending downwardly into the lighter body, a friction wheel, an axis therefor mounted in one of said bores, a wick projecting through a second one of said bores, a flint co-acting with said friction wheel, a laterally open guide sleeve for said flint, said guide sleeve having an extension pivotally engaged on the axis of the friction wheel between the friction wheel and said upper face of the lighter body and a spring urged lever rotatably mounted in the third one of said parallel bores and having a free end extending into said laterally open guide sleeve to urge the flint against the friction wheel.
